UNITED STATES PATENT OFFICE.

RICHARD VARLEY, OF ENGLEWOOD, NEW JERSEY.

X-RAY SYSTEM.

1,309,494.

Specification of Letters Patent.

Patented July 8, 1919.

Application filed March 18, 1915. Serial No. 15,270.

To all whom it may concern:

Be it known that I, RICHARD VARLEY, a citizen of the United States, residing at Englewood, in the county of Bergen and State of New Jersey, have invented certain new and useful Improvements in X-Ray Systems, of which the following is a full, clear, and exact description.

This invention relates to a system for producing currents of high frequency, density and potential suitable for X-rays and analogous purposes, the object being the provision of apparatus by which an X-ray tube may be excited by currents of comparatively high density, at a maximum efficiency of conversion, with apparatus of low cost capable of operation either direct from existing service circuits or from an alternator, a motor generator or other converting machine of small cost, size and output, and without the use of current rectifiers or other moving parts of a complex nature and requiring appreciable power in their operation.

The improved system comprises a transformer capable of producing in the secondary circuit, currents of high electro-motive force coincident with comparatively high amperage, in combination with a source of alternating current and means whereby the half waves of one polarity only of the current supplied will be effective in producing current in the secondary of the transformer, to the end that only unidirectional currents will charge the tube.

The invention contemplates the use of a transformer in which the magnetic flux is normally largely suppressed in that limb of the core upon which the secondary is located while substantially all of the flux is periodically permitted to become suddenly active in that limb, at which periods the sudden surging of the restrained flux induces an instantaneous extraordinary high electromotive force in the secondary circuit capable of jumping a wide gap between the electrodes of the tube. Due to this comparatively high electromotive force I am able to use a secondary coil of comparatively few turns and low resistance which affords a comparatively large number of milliamperes of current in the secondary circuit and a discharge in the tube of correspondingly greater density and power of "penetration."

In the accompanying drawings,
Figure 1 is a diagrammatic view of cir-

cuits and apparatus embodying my invention;

Fig. 2 is a similar view of a modification of the invention, and

Fig. 3 is a diagram of the current wave supplied to the primary circuit.

Referring to Fig. 1, G indicates a source of alternating current, which may be either a motor generator or a rotary converter, in either case delivering current from the slip rings g, g, to the primary circuit 1, 2 through a pole changing switch 3. T is a transformer having a core t in the form of a substantially closed magnetic circuit. On one side or limb of this core is a coil 4, hereinafter called the primary coil, connected with the primary circuit wires 1, 2, while upon another part or limb of the core is located a coil 5, hereinafter referred to as the secondary coil, of a comparatively larger number of turns and of finer wire than is in the primary coil, and connected in circuit with the wires 6, 7 which are connected, or to be connected, with the respective and proper terminals of an X-ray tube R. Upon the same limb of the transformer core with the secondary, is another winding 8 having the function of a choke coil and referred to hereinafter as the choke coil. The circuit of this coil is normally closed through a spring tongue 9 resting against a contact stop 10, the tongue being mounted in a position to be struck and forced away from the contact 10 by a cam disk 11 mounted upon or to be driven by, the shaft of the supply machine G, the contact at 10 being broken once during each rotation of the cam.

Assuming that the generator G delivers a sine wave current such as plotted in Fig. 3, the primary coil 4 will be correspondingly symmetrically energized setting up a magnetic flux in the transformer core t. Choke coil 8 being normally short circuited at 10 effectually acts as a choke upon the travel of lines of force through that part of the core under the choke coil and secondary coil windings. Rotation of the cam 11 in synchronous relationship with the generator causes the sudden opening of the circuit of coil 8 at a suitable point in the current wave. Opening of the circuit of coil 8, as stated, causes a disruptive discharge of current of high voltage to take place in the secondary coil 5 in circuit with the tube. When the circuit of coil 8 is opened a magnetic surge of great intensity and speed oc-

curs through the entire core of the transformer. A high voltage is immediately built up in the secondary coil 5 sufficiently to instantly bridge or break down the gap 5 between the electrodes of the tube. However, the discharge thus formed is not merely instantaneous but continues as long as the circuit of coil 8 is open. Upon the establishment of the discharge, current flows 10 in the secondary circuit and the ampere turns of the secondary coil take the place, in their effect, of the ampere turns of the coil 8. The choking effect is controlled by the arc or discharge in the tube, which assumes, by reason of its establishment in the 15 circuit of coil 5, a rheostatic function, for the voltage across the gap itself is sustained by the flux change which, in turn, is controlled by the amperage of the discharge 20 across the gap in the tube. Therefore with a certain changing of flux in the core, preferably partially sustained by the active source, increase of gap resistance decreases the current flow across the gap, allowing 25 increase of flux and so reciprocal increase of gap voltage, thus tending to current maintenance and stability. The system therefore operates to instantaneously break down the resistance of the gap in the tube 30 with a high voltage and a current of high milliamperes, as compared with a Ruhmkorff coil of equal watt intake.

Preferably, the generator G is one which 35 delivers one complete wave consisting of a positive and a negative impulse, at each rotation and the interrupting cam is so placed upon the shaft of the generator or geared thereto, that it will open the contact at 10 during only one of the impulses, say the 40 positive, in each rotation and allow the contacts to remain closed during the other or negative impulse and the remainder of the rotation, as illustrated in Fig. 3, where the full lines of the curve indicate approximately the periods during which contacts 10 45 are open and the dotted lines the periods during which they are closed. In this manner only unidirectional currents are induced in the secondary circuit, which is necessary for the production of the X-rays and the use of current rectifiers with their attendant complication and consumption of power is eliminated. And while only the current impulses of one polarity of the generator, are utilized, this is compensated for 50 by the fact that the peculiar method of transforming affords the greater electro-motive force and renders it possible to obtain a greater amperage with a given resistance 55 of secondary circuit.

It is obvious that a multipolar generator or other source at G may be used which will yield more than one impulse of a certain polarity at each rotation. For instance, a 60 four-pole machine would give two positive

and two negative impulses. In such case the cam 11 preferably would be provided with two projections diametrically opposite each other and adapted to open contact 10 during each positive or each negative wave, 70 as the case may be. The pole changing switch 3 is to be used at starting in case the discharge in the tube does not happen to be in the right direction. The cam 11 is small and light and entails little or no expenditure of power to operate it so that the converting machine G will not be burdened by its presence on the shaft. 75

Instead of the mechanical circuit opener for the choke coil circuit, I may, and in fact 80 prefer to, use an electro-magnetic device and thereby dispense with all rotating parts and the requirement of motor power at the point where the tube is to be operated. Such a system is illustrated in Fig. 2 wherein P indicates a polarized relay of which 12 is the 85 vibrating armature located between poles 13, 13 on which are wound differentially the usual electro-magnetic coils. These coils have been shown as permanently connected 90 in series with the primary circuit of the transformer, which circuit may be supplied from service mains 14, 15 and controlled by manual switch 16. They may, however, be connected in parallel with said circuit. The 95 armature of the relay is given a slight bias toward a contact stop 17 by a light spring 18 assisting the normal magnetic bias. The normal polarity of the coils 13 and armature 12 is as indicated in Fig. 2. When there is 100 a flow of current through the coils 13 in one direction the normal polarity remains unchanged and the armature 12 is drawn with a force, additional to that of the spring 18, against the contact stop 17. The opposite 105 phase of the current will reverse the polarity of the coils 13, causing the armature to be moved to the left, away from the stop 17. Armature 12 and contact 17 are the terminals of the choke coil circuit so that the 110 movements of the armature 12 due to alternations in the primary circuit serve to open and close the circuit of the choke coil and perform the same functions as the cam 11 and spring blade 9 in the system of Fig. 1. 115 The tension of spring 18 is such as to insure the prompt closure of the choke circuit immediately before the point of zero potential in the wave is reached.

The opening of the choke circuit at 17 is 120 delayed slightly but not materially by this spring but such delay is advantageous in a sense, making the surge of lines more pronounced when the choke circuit is opened nearer the peak of the wave. The exact 125 points in the half wave of opening and closing the choke circuit may be adjusted in any convenient way, as by regulating the tension of the spring in the system of Fig. 2, while in Fig. 1 different lengths of cam on disk 130

11 can be used. When sudden and excessive electro-motive forces are required to jump a wide gap, the opening may occur later or nearer the peak of the wave and when longer duration of the discharge is required the opening may occur earlier. An average serviceable location and duration for the opening period is indicated by the full lines in Fig. 3. Under some conditions of structure and operation, objectionable arcing may occur at the contacts which control the choke coil circuit, in which case it may be found desirable to connect a condenser 19 across the contacts 10 in Fig. 1 or 19 in Fig. 2. Other plans for suppressing the arc may also be adopted, such as maintaining the relay in a sealed chamber containing air or gas under pressure, or a non-oxidizing gas which will prevent destruction of the contacts.

With the apparatus herein described X-ray operations can be performed with the greatest convenience. This is especially true with the system which comprises the polarized relay, for in this case the only apparatus needed besides a source of current is the simple and cheap form of relay and the transformer which is directly connected with the tube. This apparatus can be readily conveyed to any location and operations performed by a mere attachment to ordinary service mains. The system is entirely devoid of synchronous motor driven current

rectifiers and all rotating parts which add to the complexity and expense of other systems. In connection with the system of Fig. 1 it may be remarked that while the cam disk 11 is a light and simple piece of apparatus requiring almost negligible power to drive it, nevertheless it may be dispensed with and a polarized relay inserted in the primary circuit 1, 2 and thus relieve the mechanical generator of such slight load as the disk entails.

I claim:

1. In an electric system, the combination of a source of alternating current, a transformer supplied thereby, a choke coil associated with the core of the transformer, and an electro-magnetic device actuated by the primary current of the transformer and controlling the circuit of the choke coil.

2. In an electric system, the combination of a source of alternating current, a transformer supplied thereby, a choke coil associated with the core of the transformer and a polarized relay in the primary circuit of the transformer and controlling the circuit of the choke coil.

In witness whereof I subscribe my signature, in the presence of two witnesses.

RICHARD VARLEY.
